UNITED STATES PATENT OFFICE.

FRANKLIN W. OLIN, OF ALTON, ILLINOIS, ASSIGNOR TO WESTERN CARTRIDGE COMPANY, OF EAST ALTON, ILLINOIS, A CORPORATION OF DELAWARE.

DETONATOR PACKAGE.

Application filed February 5, 1925. Serial No. 7,162.

This invention relates to prepared detonator packages utilizing a detonator of the electric ignition type.

In detonators of the type referred to, the 5 detonator cap cartridge or shell is loaded with a high explosive which is electrically ignited; accordingly the cartridge has attached thereto leading in or igniter wires for the purpose of conducting the igniting current thereto in order to effect ignition of the charge. The igniter wire is usually of considerable length and since the cartridges must be furnished with the wire attached thereto, the handling and shipping of the 10 same is rather inconvenient.

A detonator cartridge is subjected to shocks during handling and shipment and it frequently happens that explosion takes place during such handling or shipment 20 with liability of injury to life and limbs and damage to property. Accordingly for shipment these detonators must not only be carefully packed, but the accident, express and freight rates are unduly high.

25 In a detonator of the character described, the wire, including the bare terminals thereof are subjected to exposure; accordingly if they should come in contact with a source of current, explosion of the detonator is liable to take place.

One of the objects of this invention, therefore, is to provide a prepared package in which the detonator cartridge and the igniter wire attached thereto are assembled to 35 provide a compact and convenient package which can not only be readily stored and shipped, but also when required for use is so constructed and arranged as to permit the wire to be readily strung out for the 40 purpose of connection of the wire to the source of current, while the cartridge itself is in detonating position.

Another object of this invention is to provide a prepared package in which the detonator cartridge has a protective casing for 45 completely insulating the detonator.

Another object of this invention is to provide a prepared package in which not only the detonator has a protective casing, but 50 in which protective or insulating casing means is also provided for the wire and the terminals thereof.

Further objects will appear from the detail description taken in connection with the 55 accompanying drawing, in which:

Figure 1 is an elevation (somewhat enlarged) showing an embodiment of a prepared detonator package embodying this invention;

Figure 2 is a perspective view partly in section showing another embodiment of this invention; and

Figure 3 is a sectional view of the package of Figure 2.

Referring to the accompanying drawing, 65 and more particularly to Figure 1, (although reference is also had to Figures 2 and 3 in that the interior construction is substantially the same when the outer tube or casing is omitted), 1 designates the detonator cartridge or shell, which as usual is of drawn metal and contains a charge of high explosive, and 2 designates the igniter wire, which leads from and is attached to the cartridge, the wire passing through a seal 75 3 of suitable material closing the end of the cartridge and terminating inside of the shell in a filament adapted to glow when the current is passed through the wire. 80 This cartridge and its connections so far described may be of any usual and suitable construction, and a further detail description thereof is, therefore, unnecessary.

The wire is preferably wound upon a tube 4 of paper, card board or any other suitable 85 material, so as to provide a coiled casing which in this case encloses the tube as well as the cartridge. The wire is preferably coiled back and forth as shown, with the outer layer helices crossing those of the 90 inner layer and so that the cartridge attached end of the strand and the free end of the strand both terminate at one end of the coil, and these ends of the strand preferably pass through slots 5 in the end of the 95 tube. After the wire has been coiled in the manner shown and described, there is left a cartridge attached end of the strand of some length, so that the cartridge can be inserted into the coil and the tube therein 1 from the end opposite to which the strand is secured. While it is preferable to leave the tube in position, it will be obvious that after the coil has been wound on the tube, the latter can be taken out leaving a coil 1 which forms a casing, even apart from the tube; for since the coils or helices of one layer cross those of the other, the effect will be to cause one to hold the other, and the ends will, therefore, be secured since they 1

double over one another to form bights. Of course, it will be understood that the wire is insulated and is moreover of substantial cross section so as to be comparatively stiff, whereby the package will readily retain its shape.

In the embodiment shown in Figure 1, the bare terminals 6 of the wire 2 are covered with a protective casing 7 of insulating material and this casing is made long enough to project beyond the ends of the wire as shown.

In the construction shown in Figures 2 and 3, the coiled wire has placed thereover a casing 8 in the form of a tube of paper or other suitable material. This tube can be made to closely fit the wire so as to be held in place by friction; however, after the tube is in place the ends of the tube may be crimped over as shown at 9 to provide retainers or stops for holding the outer tube in place, paper caps or wads 10 having been first put in place to close the tube 8.

In order to properly identify the terminals 25 the wires 2 may be distinguished in any suitable manner, as by coloring one insulated wire while leaving the other plain, or by making the insulation on the two wires of different colors. This is indicated in the drawing by cross hatching on one wire.

The cartridge attached strand is of sufficient length to permit the cartridge to be inserted in the tube 4 after the wire has been coiled thereon. After insertion, therefore, 35 there is a loop of some length which is wrapped about the coil as shown at 11 by twisting the cartridge in the tube. The bare ends 6 may also be wrapped around the coil before inserting in the tube 8. This should 40 be done so as to bring these ends to the middle of the coil as shown in Figure 2, where they will be adequately protected and insulated by the tube 8.

It will, therefore, be seen that the invention 45 accomplishes its objects. A prepared package is provided which is compact, convenient, simple and inexpensive, while the wires and cartridge will be firmly held in assembled relation; the layers of stiff wire 50 mutually sustaining one another in order to form a self-sustained casing, while the cartridge is retained in the casing by the stiff cartridge-attached strands. The casing 7 is held on the terminals 6 by friction and 55 this can be made positive by bending or kinking the wire and casing 7. Where an outer tube 8 is used, it is held in place as described.

When it is desired to use the detonator, 60 the cartridge can be withdrawn from the casing; in the embodiment shown in Figure 1, the casing 7 is slipped off to expose the terminals 6; while in the embodiment shown in Figures 2 and 3 the outer tube is first 65 slipped off to free the wire. By then freeing

the strand from the slots 5, the wire can be readily uncoiled so as to enable connections to be made to the source of current, while the detonator is placed in the charge to be detonated in the usual manner.

It will be noted that the wire coiled around the detonator cartridge, either alone or in connection with the inner tube, provides a very strong protective casing which can withstand an explosion of the cartridge, 75 since the rupture of the cartridge shell is lateral and usually intermediate its ends where the protective casing covers it. The outer casing or tube 8 not only enhances the strength of the protective covering but also 80 prevents uncoiling of the wire. This outer tube 8 furthermore not only protects or insulates the bare terminals 6 against exposure, as does the casing 7, but also protects or insulates the wire itself against exposure; 85 the detonator is, therefore, insulated against liability of premature ignition as might occur if the wires come in contact with electrical apparatus or current carrying wires. Accordingy injury to life and limb during 90 handling and damage to property during shipment is, therefore, considerably lessened so that accident, express and freight rates can be considerably reduced.

It is obvious that various changes may 95 be made in details of construction without departing from the spirit of this invention; it is, therefore, to be understood that this invention is not to be limited to the specific details shown and described.

Having thus described the invention, what is claimed is:

1. A prepared package comprising, a detonator cartridge having current conducting wire coiled around the cartridge to provide 105 a protective casing therefor, and protective means for the wire.

2. A prepared package comprising, a detonator cartridge having current conducting wire, a tube over the cartridge and on which the wire is coiled, and a casing for the wire.

3. A prepared package comprising, a detonator cartridge having current conducting wire coiled around the cartridge to provide a protective casing therefor, the terminals 115 of the wire being provided with a protective casing.

4. A prepared package comprising, a detonator cartridge having current conducting wire coiled around the cartridge to provide a protective casing therefor, and a tube fitting over the coiled wire and providing a protective casing therefor.

5. A prepared package comprising, a detonator cartridge having current conducting wire, a tube over the cartridge and on which the wire is coiled, and a tube fitting over the coiled wire and providing a protective casing therefor.

6. A prepared package comprising, a det-

- onator cartridge having current conducting wire, a tube over the cartridge and on which the wire is coiled, a tube fitting over the coiled wire and providing a protective casing therefor, and means for retaining the parts in assembled relation.
7. A prepared package comprising, a detonator cartridge having current conducting wire coiled around the cartridge to provide a protective casing therefor, the wires being marked to distinguish them relatively.
- 10

8. A prepared package, comprising, a detonator cartridge having a current conducting wire coiled around the cartridge to provide a protective casing therefor, the end 15 of said wire being bare and coiled so as to terminate at the middle of the coil, and an insulating casing for the coil.

In testimony whereof I affix my signature this 12th day of January, 1925.

FRANKLIN W. OLIN.
